ABSTRACT OF THE DISCLOSURE

In electrical apparatus having a circuit breaker comprising an electromagnetic latching device of a U-shaped structure, having a permanent magnet disposed between its legs, an armature releasably held to the pole faces of the U-shaped structure and biased away from said structure and two magnetic circuits, one passing through the permanent magnet and the armature to hold the armature to the U-shaped structure while the other passes through the permanent magnet and the base part of the U-shaped structure.

This application is a continuation of the parent application Ser. No. 563,296, filed July 6, 1966, now abandoned, which was a continuation of application Ser. No. 407,333, filed Oct. 29, 1964, now abandoned, which was a continuation-in-part of application Ser. No. 103,635, filed April 17, 1961, now abandoned.

This invention relates generally to circuit breakers and more particularly to circuit breakers of the type having electromagnetic tripping means.

An object of this invention is to provide an improved circuit breaker embodying a magnetic device operable to effect opening of the circuit breaker.

Another object of this invention is to provide a circuit breaker embodying an improved electromagnetic latching device releasable to effect automatic opening of the circuit breaker.

Another object of this invention is to provide a circuit breaker with improved means for effecting high speed tripping operations.

Other objects of this invention will be explained fully hereinafter or will be apparent to those skilled in the art.

In accordance with one embodiment of the invention, a circuit breaker is provided comprising an electromagnetic latching device that embodies a generally U-shaped structure of magnetic material such as soft iron, having a permanent magnet disposed between its legs. An armature is releasably held to the pole faces of the U-shaped structure and is biased away from this structure. There are two separate magnetic circuits in the electromagnetic device. One of the magnetic circuits passes through the permanent magnet and the armature. The magnetic flux in this circuit works to hold the armature to the U-shaped structure. The other magnetic circuit passes through the permanent magnet and the cross-over part or base part of the U-shaped structure. Two coils are provided around one leg of the U-shaped structure on opposite sides of the permanent magnet. These coils are energized with direct current to reciprocate magnetic flux between the two magnetic circuits to cause the armature to be alternately released from the U-shaped structure and held to the U-shaped structure. When the armature is held to the U-shaped structure, it latches the circuit breaker latch

2

means in a latching position and when released it releases the latch means to effect a tripping operation.

In another embodiment of the invention, a circuit breaker is provided comprising an electromagnetic latching device that embodies a generally H-shaped structure comprising two legs of magnetic material, such as soft iron, and a permanent magnet connecting the two legs. An armature structure is provided embodying two armatures disposed at opposite ends of the H-shaped magnetic structure. The armatures are connected in a spaced relationship by means of two side members to move as a unit. The armatures are so spaced that only one armature at a time can engage the magnetic structure. This electromagnetic device comprises two alternately energized magnetic circuits. One of these magnetic circuits passes through the permanent magnet and one of the armatures, and the other circuit passes through the permanent magnet and the other armature. Two coils are provided around one of the legs of the magnetic structure on opposite sides of the permanent magnet. These coils are energized in a manner to effect reciprocation of magnetic flux between the magnetic circuits to thereby effect reciprocation of the armature structure. Reciprocation of the armature structure effects latching and tripping of the circuit breaker in a manner to be specifically described.

For a better understanding of the nature and objects of the invention, reference may be had to the following detailed description, taken in conjunction with the accompanying drawings, in which:

FIGURE 1 is a partly schematic elevational view of an electromagnetic device;

FIG. 2 is a view, partly in section and partly in elevation, of a portion of a circuit breaker utilizing the electromagnetic device of FIG. 1;

FIG. 3 is an elevational view of a modification of the electromagnetic device shown in FIG. 1;

FIG. 4 is a view, partly in elevation and partly in section, illustrating the use of the electromagnetic device of FIG. 3 in the circuit breaker shown in FIG. 2;

FIGS. 5A and 5B are graphs illustrating characteristics of the invention;

FIG. 6 is a partial view illustrating a modified form of the circuit breaker seen in FIG. 2;

FIG. 7 is a view similar to FIG. 6 and illustrating another modification of the invention;

FIG. 8 is a partial view of a modified form of the invention disclosed in FIG. 4.

Referring to the drawings and particularly to FIG. 1, an electromagnetic device 1 comprises a base 2 upon which is mounted a generally U-shaped structure 3, an armature 5 engaging the U-shaped structure, two springs 7 biasing the armature away from the U-shaped structure 3, and stop members 8 for limiting the upward movement of the armature. A lever 9, which is pivotally attached to an arm 11 that is attached to the armature 5, and which is pivotally supported by means of bracket 13, is provided for resetting the armature after an opening operation.

The U-shaped structure 3 comprises two legs 15 of magnetic material, such as soft iron, having pole faces 17 at their free ends. The legs 15 are connected by a base or cross-over part 19 of magnetic material such as soft iron. A permanent magnet member 21 is supported by means of brackets 23 between the two legs 15. The coils 25 and 27 are provided around one of the legs 15 on opposite sides of the permanent magnet member 21.

The electromagnetic device 1 is shown in FIG. 1 in the closed position. There are two separate circuits of magnetic flux provided by the permanent magnet 21 in the electromagnetic device 1. The first magnetic circuit extends from the pole N of the permanent magnet 21 through the upper part of one of the legs 15, the armature 5, the upper

part of the other leg 15 and back to the pole S of the permanent magnet 21. The second magnetic circuit extends from the pole N of the permanent magnet 21 through the lower part of one of the legs 15, the base or cross-over part 19, the lower part of the other leg 15 and back to the pole S of the permanent magnet 21.

As can be seen in FIG. 1, the coils 25 and 27 are connected to a suitable source of direct current and are controlled by operation of switches S₁ and S₂ respectively, each of which switches may be a standard type spring return push-button switch.

As will be hereinafter specifically described, when the parts are in the position shown in FIG. 1, approximately 90% of the magnetic flux emanating from the permanent magnet member 21 takes the path of the first circuit through the armature 5 working to hold the armature to the U-shaped magnetic structure 3. The other 10% of the magnetic flux takes the path of the second circuit through the cross-over part 19.

If the coil member 25 is momentarily energized, by operation of the switch S₁, to buck the magnetic flux in the first or upper circuit, this flux will then shift to take the path of least reluctance through the second or lower circuit. This shift of magnetic flux will effect release of the armature 5 from the U-shaped structure 3 and the armature 5 will move up under the bias of the springs 7 to engage the stop members 8. The armature 5 will then remain in this open position until an upward force (not shown) is applied to the outer end of the lever 9 to move the armature 5 back to the closed position shown in FIG. 1. When the armature 5 is in the closed position, the lower coil 27 can then be momentarily energized, by operation of the switch S₂, to buck the flux in the second or lower magnetic circuit, in which case the flux will shift to take the path of least reluctance through the first or upper magnetic circuit to again work to hold the armature 5 to the U-shaped magnetic structure 3.

With both coils 25, 27 then deenergized, the magnetic circuits are established with approximately 90% of the magnetic flux emanating from the permanent magnet 21 working in the first magnetic circuit and the remaining 10% of magnetic flux being in the second magnetic circuit. This circuitry so established will be stable until the upper coil 25 is again energized to buck the flux in the upper or first magnetic circuit to effect another opening operation of the electromagnetic device 1.

The "memory" action whereby the magnetic flux remains largely in the portion of the magnetic circuit where it most recently has been established can be explained by the magnetic properties of the parts, as represented typically in the curves of FIGS. 5A and 5B. The soft iron core has a hysteresis loop and the permanent magnet has a curve as shown of magnetomotive force (MMF) plotted against flux.

With the magnetic structure assembled, and with one or both coils appropriately energized with direct current, the flux through one armature or both, such as 5 of FIG. 1, will be raised from O of FIG. 5A along the dotted line to the maximum point B. At the same time the flux in the cross-over part 19 of the magnet structure will carry little flux, since with respect to this leg, the coil or coils will buck (rather than boost) the flux efforts of the permanent magnet. When the coil is de-energized, the flux in 5 of FIG. 1 will follow the curve from point B of FIG. 5A to some point such as A corresponding to a MMF of H', at which point equilibrium will exist between the permanent magnet and the soft iron magnet structure. This equilibrium point for the permanent magnet is at A' of FIG. 5B.

It is now obvious that the magnetomotive force H' available to establish flux in the second magnetic circuit through the cross-over part 19 is small and will establish little flux, since it will be acting on a circuit having a magnetization curve such as O-B of FIG. 5A. On a repetitive cycling the coil energization would be expected

to reduce the flux in the inactive circuit to substantially zero, so that it would always be given a fresh start.

Although the closing operation hereinbefore described was effected by means of applying a force to the free end of the lever 9, it can be understood that if the springs 7 are light enough, for certain applications of the electromagnetic device 1, the resetting force and lever mechanism 9, 11, 13 can be omitted, in which case, when the coil 27 is energized to buck the magnetic flux in the second or lower magnetic circuit, the flux will take the path of least reluctance through the air gaps and armature 5 to attract the armature 5 to the U-shaped structure and pull the armature to the closed position without the aid of any external mechanical resetting force.

As was specifically described, the coils 25 and 27 were alternately energized to buck the magnetic flux or increase the reluctance in their respective circuits to effect a transfer of magnetic flux between the two magnetic circuits. It is to be noted that the coils 25 and 27 could be wound with a polarity such that the coil 27 would be energized to effect a decrease of the reluctance in the second or lower magnetic circuit to effect a transfer of magnetic flux from the upper magnetic circuit to the lower magnetic circuit to effect release of the armature 5, and such that the coil 25 would be energized to effect a decrease of the reluctance in the first or upper magnetic circuit to effect a transfer of magnetic flux from the lower magnetic circuit to the upper magnetic circuit to effect attachment of the armature 5 to the U-shaped structure 3.

Another method of operation would be to connect and energize the coils 25 and 27 simultaneously in such a manner that when the reluctance of one of the magnetic circuits is increased, the reluctance of the other circuit will be simultaneously decreased to effect a transfer of magnetic flux from the one to the other magnetic circuit. Transfer of magnetic flux back from the other to the one magnetic circuit would then be facilitated merely by reversing the direction of the flow of current in the coils 25, 27.

The electromagnetic device 1 is shown in FIG. 2 embodied in a circuit breaker 31 that comprises an operating mechanism 33 and a contact structure 35. The circuit breaker 31 is of the type specifically described in the patent to F. E. Florschutz et al., Patent No. 2,647,182, assigned to the assignee of the instant application. The contact structure 35, which is illustrated diagrammatically, may be of any conventional construction, either an oil-break, air-break or a gas-blast type, and it is adapted to be operated to the open position by means of an accelerating spring 37. The circuit breaker 31 is operated to the closed position by means of the operating mechanism 33 which, in the embodiment shown, is of the compressed-fluid type.

The operating mechanism 33 includes an operating cylinder 39 which is closed at its upper end by a plate 41 that is secured to the cylinder 39 by means of bolts (not shown). An operating piston 43 is mounted in the operating cylinder 39 and has secured thereto a piston rod 45 that is slidable through an air-tight opening in the plate 41. Rigidly secured to the upper end of the piston rod 45, is a coupling 47 that is releasably connected to a coupling 49 by means of an inverted or overlapping toggle comprising toggle links 53 and 55. The coupling 49 is secured to a breaker operating rod 56 in a suitable manner. The breaker operating rod 56 is operatively connected to the circuit breaker contact structure 35 by means of a suitable linkage.

The toggle link 53 comprises a pair of spaced parallel links pivotally connected by means of a pivot pin 57, to the coupling 47. The toggle link 55 comprises a single link which is disposed between the links 53 and which is pivotally connected by means of a pivot pin 59 to the coupling 49. The toggle links 53 and 55 are pivotally connected, together by means of a knee pivot pin 61.

In order to provide a straight-line movement on the

piston rod 45 and the breaker operating rod 56, and to assist the trip-free toggle 53, 55 in maintaining the breaker closed, the pivot pins 57 and 59 are provided with rollers 63, there being a roller 63 mounted on each end of each of the pivot pins 57 and 59. These rollers cooperate with corresponding vertical slots 65 formed in a pair of spaced frame members 67 that are rigidly mounted on the plate 41 and that extend upwardly in a spaced parallel relation. In order to provide suitable bearing surfaces for the rollers 63, plates 69 are provided with slots coinciding with the slots 65 and are secured to the outside of each of the frame members 67 in any suitable manner, preferably by welding.

The circuit breaker is held in the closed position by means of a main latch 71 and a light load latch mechanism indicated generally at 73. The main latch 71 is pivotally mounted on a pin 75 which is supported in the frame members 67. The main latch 71 is biased by means of a spring pressed plunger 77 into the latching position engaging a latching surface 79 on the coupling 47. The plunger 77 is slidably mounted in an opening in a cross bar 81 that is rigidly supported between the frame members 67, and the plunger is biased by means of a compression spring 83 that is compressed between the cross bar 81 and a washer 85 on the plunger. The main latch 71 is provided with a latching surface 87 for cooperating with the latching surface 79 on the coupling 47 and it also has a downwardly extending projection 89, the purpose of which will be described later.

The light-load latching mechanism 73 includes an under-set tripping toggle comprising toggle links 91 and 93, and a trigger latch 95 operating to releasably maintain the tripping toggle in its under-set position. The toggle link 91 comprises a pair of links rigidly joined by a cross member 97 which links are pivotally mounted on a fixed pivot pin 99 supported by the frame members 67. At their free ends, the toggle links 91 carry between them a latch roller 101 with which the trigger latch 95 cooperates to maintain the tripping toggle 91, 93 in its under-set position. The toggle link 93 comprises a pair of spaced parallel links disposed one on each side of the link 91 and pivoted on the knee pivot pin 61 of the trip-free toggle 53, 55 outside of the toggle links 53. The toggle links 93 are pivotally connected to the toggle link 91 by means of a knee pivot pin 103.

The trigger latch 95 is pivotally mounted on a pivot pin 105 supported in a pair of spaced brackets 107 (only one being shown) which in turn are rigidly secured to a cross plate 109 that is mounted on the frame member 67. The trigger latch 95 is biased to latching position by means of a spring 111 disposed between the cross plate 109 and an extension 113 of the latch 95. The latching position is determined by engagement of a tail portion 115 of the latch 95 with the cross plate 109. The armature 5 of the electromagnetic device 1 is connected to the trigger latch 95 by means of a pivot pin 117. The electromagnetic device 1 is supported on a bracket 119 that is rigidly secured to the side plates 67.

The main latch 71 holds the piston 43 in the closed position shown in FIG. 2 against the force of two nested springs 121 that are compressed between the bottom of the piston 43 and the bottom of a downwardly extending cylindrical portion 123 of the cylinder 39. The accelerating spring 37 applies an upward force on the breaker operating rod 56. Since the pivot pins 57 and 59 are constrained by the slots 65 to move in a straight-line, a small component of this upward force is applied through the link 55 to the tripping toggle 91, 93. Since the tripping toggle 91, 93 is only slightly underset, a very small component of the force of the accelerating spring 37 is applied through the tripping toggle 91, 93 biasing the link 91 in a counterclockwise direction about the pivot 99. This movement is restrained by the roll-off type engagement of the latch roller 101 with the trigger latch 95. The magnetic flux in the first or upper circuit of the electromagnetic device 1

cooperates with a spring 111 to hold the armature 5, and the trigger latch 95 to which the armature is secured, in the closed latching position shown.

The coils 25 and 27 (FIG. 2) are connected to a suitable source of DC power. The coil 25 is energized by a closing operation of the switch SP₃ which switch may be a spring return manually operable push-button switch. The coil 25 will also be energized upon the occurrence of predetermined overload current conditions in the circuit controlled by the breaker, by automatic operation of the switch SA₃ to the closed position. The switch SA₃ can be closed automatically, for example, by means of a relay that is connected to be actuated upon the occurrence of an overload current in the circuit that is to be controlled by the breaker. The switch S₄ is a limit switch that is operated to be closed by the pin 59 when this pin reaches its fully open position (not shown) at the top of the slot 49.

In the closed position shown in FIG. 2, the larger portion of magnetic flux in the electromagnetic device 1 works in the upper magnetic circuit to hold the armature 5 in the closed position to thereby hold the trigger latch 95 and the circuit breaker 31 in the closed position. When either of the switches SA₃ or SP₃ is momentarily closed, the coil 25 of the electromagnetic device 1 is energized to buck the flux in the upper magnetic circuit to transfer flux to the lower magnetic circuit to effect release of the armature 5. Upon release of the armature 5, the force of the opening spring 37, acting through the link 55 and tripping toggle 91, 93, forces the roller 101 to move the latch 95 counterclockwise out of latching position to release the tripping toggle 91, 93. The force of the opening spring 37 causes the tripping toggle 91, 93 to collapse moving the link 91 in a counterclockwise direction about the pivot 99. As soon as the tripping toggle 91, 93 starts to collapse, the breaker operating rod 56 starts to move upwardly to open the contact structure 35. The upward movement of the breaker operating rod 56 and the collapse of the tripping toggle 91, 93, causes clockwise rotation of the trip-free toggle link 53. When the breaker rod 56 has traveled upwardly a very short distance, approximately 1/2 of an inch, a tail portion 125 on the toggle link 53 engages the projection 89 on the main latch 71 and cams the main latch 71 to unlatching position releasing the piston rod 45, whereupon the powerful springs 121 thrust the piston 43 and the piston rod 45 upwardly at a speed greater than the opening speed of the breaker operating rod 56. The piston rod 45 and operating rod 56 are moved upwardly by the force of the springs 121 to open the circuit breaker. Since the pivot pins 57 are constrained by the slot 65 to travel in a straight line and the speed of upward movement of the pin 57 is greater than the speed of upward movement of the pin 59, the toggle link 53 will cause the link 55 to rotate counterclockwise about the pivot pin 59 toward the inverted position of the toggle 53, 55. This action through the pin 61 and link 93 rotates the link 91 clockwise about its pivot 99 far enough to permit reengagement of the spring biased trigger latch 95 under the latch roller 101. This action also recouples the piston rod 45 to the breaker operating rod 56 and the parts thereafter travel in unison to the full open position of the breaker moving the piston 43 to the top of the cylinder 39. When the pin 59 reaches its fully open position at the top of the slot 49, it operates to close the limit switch S₄. This energizes the coil 27 to buck the flux in the lower magnetic circuit, in the same manner previously described, whereupon the flux again works to hold the armature 5 in the latched position.

The circuit breaker is closed by admitting compressed gas to the operating cylinder 39 above the piston 43, by means not shown. This forces the piston 43 and the piston rod 45 downward drawing the link 53 downward. Since the toggle link 91 of the tripping toggle 91, 93 is

now latched, the link 93 pivots about its pivot pin 103 which acts as a fixed pivot, thereby holding the toggle 53, 55 in thrust transmitting position during the closing operation. The closing force applied to the link 53 is, therefore, transmitted through the link 55 to move the breaker operating rod 56 downward to close the breaker.

Referring to FIG. 3, there is shown therein an electromagnetic device 141 comprising a guide member 145 supported on a base 143. An H-shaped magnetic structure 147 comprises two magnetic legs 149 and a permanent magnet member 151 supported between the two legs by means of brackets 153. The brackets 153 are secured to an upwardly extending portion 155 of the guide member 145 to thereby support the magnetic structure 147. An armature structure indicated generally at 157 comprises two magnetic armatures 159 and 161 supported on opposite sides of the H-shaped magnetic structure 147 and rigidly held in a spaced relationship by means of two side members 163. Two coils 165 and 167 are disposed on one leg 149 of the H-shaped magnetic structure 147 on opposite sides of the permanent magnet member 151. The side members 163 of the armature structure 157 are of such a length that only one armature 159 or 161 can engage the H-shaped magnetic structure 147 at a time.

In the position shown in FIG. 3, about 95% of the magnetic flux emanating from the permanent magnet member 151 works in a first or upper magnetic circuit passing from the permanent magnet 151 through the upper portion of one of the legs 149, the upper armature 159, the upper portion of the other leg 149, and back through the permanent magnet 151 to hold the armature 159 to the magnetic structure 147. The remaining approximately 5% of the magnetic flux emanating from the permanent magnet member 151 passes through the magnetic member 151, through the lower end of one of the legs 149, an air gap between the said lower leg and the armature 161, the armature 161, an air gap between the armature 161 and the other leg 149, the lower end of the other leg 149 and back through the permanent magnetic member 151.

When it is desired to operate the electromagnetic device 141, the coil 165 is momentarily energized, by operation of a spring return push-button switch S₅, to buck the magnetic flux in the first or upper magnetic circuit whereupon this flux takes the path of least reluctance through the second or lower magnetic circuit drawing the armature 161 and therefore the armature structure 157 upwardly as seen in FIG. 3 to a position in which the armature 161 engages the H-shaped magnetic structure 147. After energization of the coil 165, approximately 95% of the magnetic flux emanating from the permanent magnet member 151 will work through the second or lower magnetic circuit to hold the armature structure 157 in the upper position, and the remaining approximately 5% of magnetic flux will flow through the first or upper magnetic circuit which, at this time, comprises two air gaps between the upper ends of the legs 149 and the upper armature 159. When it is desired then to effect a return of the armature structure 157 to the position in which it is shown, the lower coil 167 is energized, by operation of a spring return push-button switch S₆, to buck the flux in the second or lower magnetic circuit whereupon the magnetic flux returns to the upper or first magnetic circuit to again attract the armature 159 and therefore the armature structure 157 back to the position in which it is shown.

It can be understood that the electromagnetic device 141 is a memory device in that the armature structure 157 will remain in the position to which it is moved upon momentary energization of the proper coil 165 or 167. The electromagnetic device 141 can be used for a number of specific applications. For example, it could be used as a two position relay operable by momentary coil energization with positive mechanical loading in each direction. Another use of the electromagnetic device 141 would be as a vibration relay or contactor operated by means of

energizing the coils 165 and 167 with an alternating current voltage.

The electromagnetic device 141 is shown in FIG. 4 as a magnetic latching device for a circuit breaker of the type shown in FIG. 2. In this case, the armature structure 157 is attached to the trigger latch 95 by means of the pivot pin 117. The device 141 is shown in the latched or closed circuit position. In order to effect an opening operation, the upper coil 165 is energized, by operation of either of the switches S_{A3} or S_{P3}, to buck the magnetic flux in the first or upper magnetic circuit to effect upward movement of the armature structure 157 to move the trigger latch 95 in a counterclockwise direction about the pivot pin 105 to effect an opening operation of the circuit breaker in the same manner previously described. The armature structure 157 and the trigger latch 105 are reset when the pin 59 (FIG. 2) reaches its fully open position, at the top of the slot 65, to engage and operate the limit switch S₄. Operation of the limit switch S₄ energizes the coil 167 to move the armature structure back to the latched position. The circuit breaker can then be closed in the same manner hereinbefore described.

As was described in relation to the electromagnetic device 1, the coils 164 and 167 of the electromagnetic device 141 can be energized alternately to either buck the magnetic flux in their associated circuits, or to magnetize their associated circuits; or they may be connected in series or in parallel and energized so that when one of the coils magnetizes its associated circuit, the other coil will buck the magnetic flux in its associated circuit to thereby effect a more positive transfer of flux between the magnetic circuits.

Different modifications of the invention are disclosed in FIGS. 6, 7 and 8. In each of these figures, only the circuit breaker latch means is shown, it being understood that the other parts of the circuit breaker, in each case, are the same as those parts that were hereinbefore described with reference to FIG. 2. In FIGS. 6 and 7, those parts that are the same as parts previously described with reference to FIG. 2 are identified by the same reference characters used in FIG. 2. In FIG. 8, those parts that are the same as parts previously described with reference to FIG. 4 are identified by the same reference characters used in FIG. 4.

Referring to FIG. 6, when the switches S₈ and S₉ are both closed, the coil 27 is energized to increase the reluctance in the lower magnetic circuit to thereby effect a transfer of magnetic flux from the lower magnetic circuit to the upper magnetic circuit in the same manner hereinbefore described. This transfer of magnetic flux operates to secure the armature 5 and the latch 95 in the latching position. The switch S₈ is a limit switch that is engaged and automatically operated to the closed position when the pin 59 (FIG. 2) reaches the top of the slot 65. The switch S₉ is a limit switch that is engaged and automatically operated to the closed position when the latch 95 reaches the latching position disclosed in FIG. 2. When the latch 95 reaches the latching position disclosed in FIG. 2, the armature 5, which is pivotally secured to the latch 95 by means of the pin 117, engages the pole faces of the U-shaped magnetic structure 3. The switch S₉ is provided to protect against the possibility of having a momentary energization of the coil 27 at a time before the armature 5 in the latching position. With the provision of the switches S₈ and S₉ in electrical series, the coil 27 will be energized to increase the reluctance in the lower magnetic circuit only when the circuit breaker is open and only when the armature 5 and latch 95 are in the latching position. Thus, energization of the coil 27, even if it is a momentary energization during a rapid successive opening and closing operation of the breaker, will operate to effect a transfer of magnetic flux to the reset armature 5 to latch the armature 5 and latch 95 in the latching position to thereby prepare the circuit breaker

65
70
75

for a closing operation in the same manner as was hereinbefore described.

Since the pin 59 will be at the upper end of the slot 65 while the circuit breaker is maintained in the opened position, and because the latch 95 will reach the latching position disclosed in FIG. 2 when the circuit breaker is in the opened position, the coil 27 will be continuously energized during the time that the circuit breaker is open. If it is desired to provide means for preventing continuous energization of the coil 27, while the circuit breaker is open, a relay 181 (FIG. 7) may be provided to cut off the flow of current through the coil 27. Referring to FIG. 7, the relay 181 comprises a contact structure 183, a coil 185, a coil 186 and a dashpot 189. When the circuit breaker is closed, the relay is in the normally closed position seen in FIG. 7. When the switches S_8 and S_9 are closed in the same manner hereinbefore described to effect energization of the coil 27, the relay coil 187 is energized to operate the relay contacts 183 to the open position thereby breaking the circuit through the coil 27. In the structure disclosed in FIG. 7, the relay coil 187, rather than the coil 27, is continuously energized when the circuit breaker is closed, the relay is in the normally 15 189 is provided to delay opening of the relay contacts 183 after the coil 187 has been energized to thereby provide that the coil 27 will be adequately energized to effect a shift of magnetic flux back up through the armature 5 when the latch 95 is in the latching position. With the armature 5 and the latch 95 in the latching position disclosed in FIG. 2, the circuit breaker can be operated to the closed position in the same manner as was hereinbefore described.

Referring to FIG. 8, there is disclosed therein the latching device of FIG. 4 and a normally open limit switch S_8 that is engaged and operated to the closed position automatically when the pin 59 reaches the upper end of the slot 65. The relay 181 is the same relay that was described with reference to FIG. 7. The relay 181 is operated in the same manner as was hereinbefore described to break the circuit through the coil 167 thereby providing that the relay coil 187 rather than the latching coil 167, will be continuously energized when the circuit breaker is in the open position.

In each of the circuit breakers disclosed in FIGS. 2, 4, 6, 7 and 8, the magnetic latch and coil arrangement could be adapted to effect a transfer of magnetic flux by either increasing the reluctance in the magnetic circuit from which the flux is to be transferred or decreasing the reluctance in the magnetic circuit to which the flux is to be transferred. As was hereinbefore set forth with regard to the structures disclosed in FIGS. 1 and 3, it may be desirable in some applications to simultaneously increase the reluctance in one magnetic circuit and decrease the reluctance in the other magnetic circuit to effect a transfer of flux from the one to the other magnetic circuit.

From the foregoing, it can be understood that there is provided by this invention an improved circuit breaker comprising a magnetic latch that can be released quickly with a minimum of energy input into the coils. In view of this fast latch release, the circuit breakers of this invention are particularly useful in situations where high-speed opening of the contacts is required.

While the invention has been disclosed in accordance with the provisions of the patent statutes, it is to be understood that various changes in the structural details and arrangement of parts thereof may be made without departing from some of the essential features of the invention.

I claim as my invention:

1. A circuit breaker comprising a stationary contact, a movable contact cooperable with said stationary contact, an operating mechanism releasable to effect opening of said contacts, a latching mechanism releasable to release said operating mechanism, tripping means comprising

ing a magnetic device, said magnetic device comprising a magnetic structure comprising two generally parallel pole pieces, each of said pole pieces having a pole face at a first end of said magnetic structure, said magnetic structure comprising a cross-over part connecting said pole pieces, flux-supplying means positioned between said pole pieces in a position between said pole faces and said cross-over part, an armature in a latching position attracted to said pole faces, said armature upon release thereof moving away from said pole faces to release said latching mechanism, said magnetic device comprising a first magnetic circuit and a second magnetic circuit, said flux-supplying means supplying the magnetic flux for said first and second magnetic circuits, the magnetic flux in said first magnetic circuit working to maintain said armature in said latching position, and means for transferring magnetic flux from the first to the second magnetic circuit to release said armature to thereby effect opening of said contacts.

2. A circuit breaker according to claim 1, said first magnetic circuit comprising said armature, said second magnetic circuit comprising said cross-over part, and said means for transferring magnetic flux from said first to said second magnetic circuit comprising electrical input means.

3. A circuit breaker according to claim 2, and means operable to reset said armature in said latching position and to return magnetic flux to said first magnetic circuit whereupon said first magnetic circuit works to maintain said armature in said latching position, and means operable when said armature is maintained in said latching position to close said contacts.

4. A circuit breaker according to claim 1, and said flux supplying means comprising a permanent magnet member.

5. A circuit breaker according to claim 3, and said flux supply means comprising a permanent magnet member.

6. A circuit breaker according to claim 1, said magnetic structure comprising a generally U-shaped magnetic structure with said pole pieces being the legs and with said cross-over part being the bight portion of said generally U-shaped magnetic structure, and said flux-supplying means comprising a permanent magnet member.

7. A circuit breaker according to claim 3, and said means operable to reset said armature and return magnetic flux to said first magnetic circuit comprising another electrical input means.

8. A circuit breaker according to claim 7, said magnetic structure comprising a generally U-shaped magnetic structure with said pole pieces being the legs and with said cross-over part being the bight portion of said generally U-shaped magnetic structure, and said flux-supplying means comprising a permanent magnet member.

9. A circuit breaker comprising, in combination, a stationary contact, a movable contact cooperable with the stationary contact to open and close the breaker, releasable latching means latching the circuit breaker in the closed position, tripping means comprising a magnetic structure, an armature releasably attached to the magnetic structure and releasable therefrom to effect release of the latching means to thereby effect opening of the circuit breaker, a first magnetic circuit passing through the armature to hold the armature to the magnetic structure, a second magnetic circuit separate from the armature, a first electrical input operable to effect a transfer of magnetic flux from the first magnetic circuit to the second magnetic circuit to effect release of the armature to thereby effect opening of the circuit breaker, means for resetting the armature and relatching said latching means, a second electrical input operable only after said armature is reset and said latching means is relatched to effect a transfer of magnetic flux from the second magnetic circuit to the first magnetic circuit to return the electromagnetic tripping means to the state in which the flux in the first magnetic circuit operates to hold the armature to the magnetic

structure, and means for closing said circuit breaker whereupon said armature maintains said latching means in the latching position to thereby maintain said circuit breaker in the closed position.

10. A circuit breaker according to claim 9, said magnetic structure comprising a generally U-shaped structure comprising two leg parts and a cross-over part, flux-supplying means extending between the leg parts and positioned between the cross-over part and the free ends of the leg parts, said armature being releasably attached to said U-shaped magnetic structure at the free ends of the leg parts of the U-shaped magnetic structure, said first magnetic circuit being independent of said cross-over part and passing through said armature and through said flux-supplying means, said second magnetic circuit being independent of said armature and passing through said cross-over part and through said flux supplying means, and said flux supplying means comprising a permanent magnet member.

11. A circuit breaker according to claim 10, and switch means operating automatically when said latching means is relatched to effect operation of said second electrical input.

12. A circuit breaker comprising, in combination, a stationary contact, a movable contact cooperable with the stationary contact to open and close the breaker, an operating mechanism releasable to effect opening of said contacts, a latching mechanism releasable to release said operating mechanism, a magnetic trip device comprising a magnetic structure having first pole face means at one end thereof and second pole face means at the other end thereof, an armature structure comprising a first armature opposite said first pole face means and a second armature opposite said second pole face means, said armature structure comprising connecting means connecting said first and second armatures in a spaced relationship for unitary movement, and electrical input means operable to effect movement of said armature structure to release said latching mechanism to thereby effect opening of the circuit breaker.

13. A circuit breaker according to claim 12, said connecting means connecting said first and second armatures in a spaced relationship such that only one armature at a time can be in an attracted position attracted to the associated pole face means, said electrical input means being operable to effect movement of said armature structure back and forth to effect alternate positioning of said first armature against said first pole face means and said second armature against said second pole face means, and the movement in one direction of said armature structure effecting release of said latching mechanism.

14. A circuit breaker according to claim 12, said circuit breaker being closed and said first armature being in an attracted position in close proximity to said first pole face means to position said armature structure in a first position to releasably latch said latching means in latching position, said electrical input means upon momentary energization thereof effecting movement of said armature structure to a second position wherein said first armature is positioned out of said close proximity with said first pole face means and wherein said second armature is positioned in an attracted position in close proximity to said second pole face means to thereby effect release of said latching mechanism, and means operating upon release of said latching mechanism to effect opening of said contacts.

15. A circuit breaker according to claim 14, and said magnetic structure comprising a generally H-shaped structure comprising two legs of magnetic material and a permanent magnet flux supplying member disposed between said legs, each of said legs having a pole face at each of its opposite ends, said first pole face means comprising the

pole faces at one end of said H-shaped structure and said second pole face means comprising the pole faces at the other end of said H-shaped structure.

16. A circuit breaker according to claim 12, said magnetic structure comprising a generally H-shaped structure comprising two legs of magnetic material and a permanent magnet flux supplying member disposed between said legs, each of said legs having a pole face at each of its opposite ends, said first pole face means comprising the pole faces at one end of said H-shaped structure and said second pole face means comprising the pole faces at the other end of said H-shaped structure, said circuit breaker being closed and said first armature being in an attracted position in close proximity to said first pole face means to position said armature structure in a first position releasably latching said latching mechanism, the flux generated by said permanent magnet working through said first armature to maintain said armature structure in said first position, and upon momentary energization of said electrical input means said armature structure moving to move said first armature out of close proximity to said first pole face means and to move said second armature into close proximity to said second pole face means thereby moving said armature structure to a position releasing said latching mechanism to thereby release said operating mechanism to thereby effect opening of said circuit breaker, and means for returning said armature structure to said first position and closing said circuit breaker.

17. A circuit breaker comprising a stationary contact, a movable contact cooperable with said stationary contact, an operating mechanism releasable to effect opening of said contacts, a roll-off type latching mechanism releasable to release said operating mechanism, and a double-magnetic-circuit magnetic device latching said latching mechanism and operable to release said latching mechanism.

18. A circuit breaker comprising a pair of cooperable contacts, an operating mechanism releasable to effect opening of said contacts, a latching mechanism in a latching position releasable to release said operating mechanism, a magnetic device comprising a permanent magnet providing magnetic flux to restrain said latching mechanism in said latching position, and said magnetic flux being transferable in said magnetic device to effect release of said latching mechanism.
